Atty.

UNITED STATES PATENT OFFICE.

FRITZ SCHORI, OF WETZIKON, SWITZERLAND, ASSIGNOR TO THE FIRM BAUER A. G.,
OF ZURICH, SWITZERLAND.

PADLOCK.

Application filed October 22, 1927. Serial No. 227,990.

The object of the present invention is to overcome the disadvantage inherent to padlocks of the known type that their casing shows points formed by rivet heads or 5 other projecting parts which are liable to be attacked when the padlock is forcibly opened by means of tools.

This purpose is obtained with the padlock according to the present invention in that 10 the casing which receives the shackle is closed by a cover pressed into the casing, the cover being housed in a part of the casing which is machined out of a solid piece of material.

15 Thus the padlock affords an increased security against being opened.

A constructional example of the subject matter of the present invention is illustrated on the accompanying drawings, in 20 which

Fig. 1 is an elevation view of the padlock with the cover removed,

Fig. 2 is a vertical section,

Figs. 3 and 4 show horizontal sections 25 along the lines III—III and IV—IV respectively in Fig. 1,

Fig. 5 shows the tumblers in their inoperative position.

The casing of the padlock consists only 30 of the two parts 1 and 2 of which the first is worked out of a solid piece of material, whilst 2 designates the cover pressed into the part 1 and forming the rear wall of the casing. To the circular joint 3 on the rear 35 side of the casing corresponds a circular groove 4 on the front side and for misleading unauthorized persons attempting to open the lock; the cover 2 is flush with the rear facing of the part 1. Inside the casing a key-guide 6 serving to guide the flat key 5 is arranged and recessed in the front wall as well as in the rear wall of the casing. The key-guide 6 is provided with a portion of a reduced diameter having two 45 flat facings 6' arranged opposite each other. On this reduced portion of the key-guide 6 a disk 7 is mounted, carrying two pins 8 arranged diametrically opposite each other and projecting with their free ends into

50 bores provided in the front part of the key-guide 6; thus the disk 7 takes part in the turning of the key-guide 6. On the two pins 8 two similar groups of tumblers are mounted and the tumblers of one group are 55 designated by 9 and those of the other

group by 10. The tumblers 9 and 10 are provided with projections 9' and 10' and the projections 9' are opposed to the projections 10'. The projections 9' and 10' co-operate with their oblique facings with 60 oblique facings 11' and 12' respectively formed by recesses in the casing part 1. The tumblers 9 and 10 are influenced by springs 13 and 14 respectively fixed with their one ends to the tumblers and bearing 65 with their free ends against the casing part 1; in their position of rest illustrated in Fig. 1 the lower projections of the tumblers co-operate with the facings 11 and 12 respectively whereby the key guide 6 for the 70 key and the lock are locked.

The disk 7 arranged on the key-guide 6 is provided with a cam 7' adapted to co-operate with a two armed locking lever 15 mounted on a pivot pin 16 which is provided on a pin 17 inserted in a recess of the casing part 1. A compression spring 18 tends to maintain the locking lever 15 in its operative position in which its two arms enter recesses provided in the shackle 19 80 and secure the latter in the closed position. The shackle 19 has two shanks of unequal length, of which the longer one serves as guide part to which end a pin 20 inserted in the casing part 1 cooperates 85 with a slot 21 of the shackle 19. In a bore of the guide shank of the shackle 19 a compression spring 22 is lodged which bears with its other end on the bottom of a bore provided in the casing for the reception of 90 the guide shank of the shackle.

On introducing the proper flat key 5 into the key-guide (to the required depth) the tumblers 9 and 10 are angularly displaced about the pins 8 so that their lower projecting noses 9', 10' move out of engagement with the corresponding oblique facings 11' and 12' whereby the key-guide 6 guiding the key is unlocked. By a subsequent turning of the key 5 the locking lever 15 is turned against the action of the compression spring 18 by means of the cam 7' of the disk 7 and moved out of engagement with the shackle 19. The latter is thereupon thrust out of the casing 1, 2 by 100 the action of the compression spring 22 to such an extent that its shorter shank is at a distance from the casing, whereby the padlock may be removed from the object 105 to which it has been applied; to that end 110

the shackle 19 pushed out of the casing may be turned about its longer shank serving as axis of rotation as the guide slot 21 ends in a portion 21' (Fig. 1) arranged at 5 right angles to the slot 21 to permit the turning of the shackle.

The shackle 19 may again be brought into the closing position and locked when the locking lever 15 has been brought into the 10 locking position by turning the cam 7' and key-guide 6 respectively in the opposite direction to which it has been turned for opening the lock.

If a key is inserted into the guide 6 which 15 causes an excessive turning of the tumblers 9 and 10 their upper projections 9' and 10' respectively cooperate with the upper facings 11' and 12' respectively and are pressed against the latter when the key is turned so 20 that an unlocking of the lock is prevented. The oblique facings on the tumblers cause, when an increased power is exerted by turning the wrong key, these facings to more and more deviate in the outward direction 25 and the locking is increased thereby.

The casing of the above described padlock has no projecting parts, whereby a forcible opening of the lock is rendered more difficult.

30 I claim:

1. A padlock, comprising a casing provided with facings, a key-guide rotatably mounted in said casing and adapted to receive a flat key, two pins connected to said key-guide, two groups of tumblers turnably mounted on said pins and provided with projections cooperating with said facings of the casing, a shackle operatively connected to said casing, means for locking the shackle 35 and means on the guide for operating the locking means.

2. A padlock, comprising a casing provided with facings, a key-guide rotatably mounted in recesses in the front wall and in 45 the rear wall of said casing and adapted to receive a flat key, two pins connected to said guide, two groups of tumblers turnably mounted on said pins and provided with projections cooperating with said facings of the casing, a shackle operatively connected to said casing, means for locking the shackle 50 and means on the guide for operating the locking means.

3. A padlock, comprising a casing provided with facings, a key-guide rotatably 55 mounted in recesses in the front wall and in the rear wall of said casing and adapted to receive a flat key, two pins connected to said guide, two groups of tumblers turnably mounted on said pins and provided with projections cooperating with said facings of the casing, a shackle operatively connected to said casing, means to lock the shackle and a cam operatively connected to said key-guide and adapted to operate said locking 60 means to unlock said shackle.

4. A padlock, comprising a casing provided with facings, a key-guide rotatably mounted in recesses in the front wall and in the rear wall of said casing and adapted 65 to receive a flat key, two pins connected to said guide, two groups of tumblers turnably mounted on said pins and provided with projections cooperating with said facings of the casing, a shackle operatively connected to said casing, means to lock the shackle and a cam operatively connected to said key-guide and adapted to operate said locking 70 means to unlock said shackle.

5. A padlock comprising a casing, a rotatable key guide therein, flat tumblers mounted on the key-guide, a cam on the key-guide, a shackle having a notch in each shank, a spring-urged locking lever pivoted in the 75 casing between the shanks of the shackle and in the path of said cam and normally engaging said notches.

6. A padlock comprising a casing, a shackle each leg of which has a notch, a spring-urged lever pivoted in the casing and 80 engaging both notches, a key-guide rotatably mounted in the casing whose longitudinal axis lies across the axis of said lever, tumblers pivoted between their ends on said 85 guide, one end of said tumblers normally engaging facings on the casings, and the other ends arranged to engage similar facings when an oversized key is used, and a cam on the guide arranged to laterally engage 90 and swing said lever out of the notches.

In testimony whereof I have signed my name to this specification.

FRITZ SCHORI.
